US0D1013736S

(12) **United States Design Patent** (10) **Patent No.:** **US D1,013,736 S**
(45) **Date of Patent:** **** Feb. 6, 2024**

(54) **CONSTRUCTION MACHINE**

(71) Applicant: **TRACTO-TECHNIK GMBH & CO. KG**, Lennestadt (DE)

(72) Inventor: **Wolfgang Schmidt**, Kirchhundem (DE)

(73) Assignee: **TRACTO-TECHNIK GmbH & Co. KG**, Lennestadt (DE)

(**) Term: **15 Years**

(21) Appl. No.: **29/699,447**

(22) Filed: **Jul. 25, 2019**

(51) LOC (14) Cl. **15-03**

(52) U.S. Cl.

USPC **D15/21**; D15/31

(57) **CLAIM**

The ornamental design for a construction machine, as shown and described.

DESCRIPTION

FIG. 1 is a top right rear perspective view of an embodiment of a construction machine in a transport position showing my new design;

FIG. 2 is a rear view thereof;

FIG. 3 is a front view thereof;

FIG. 4 is a top view thereof;

FIG. 5 is a bottom view thereof;

FIG. 6 is a right side view thereof; and,

FIG. 7 is a left side view thereof.

The ornamental design which is claimed is shown in solid lines in the drawings. The broken lines in the drawings form no part of the claimed design.

1 Claim, 7 Drawing Sheets
